Primary Examiner—James M. Gandy*Assistant Examiner*—M. H. Tung*Attorney, Agent, or Firm*—Zarley, McKee, Thomte, Voorhees & Sease; Mark D. Frederiksen[57] **CLAIM**

The ornamental design for an equine dental float, as shown and described.

DESCRIPTION

FIG. 1 is a top perspective view of an equine dental float showing my new design, the broken line drawing of a handle is for illustrative purposes only and forms no part of the claimed design, the handle rod is shown broken away to indicate an indeterminate length;

FIG. 2 is top plan view thereof;

FIG. 3 is an end elevational view taken from the left end of FIG 2;

FIG. 4 is a front elevational view taken from the front of FIG. 2, the rear elevational view is a mirror image;

FIG. 5 is an end elevational view taken from the right end of FIG. 2;

FIG. 6 is a bottom plan view thereof;

FIG. 7 is a perspective view of a second embodiment thereof, the broken line drawing of a handle is for illustrative purposes only and forms no part of the claimed design, the handle rod is shown broken away to indicate an indeterminate length;

FIG. 8 is a top plan view of the embodiment of FIG. 7;

FIG. 9 is a left end view taken from the left end of FIG. 8;

FIG. 10 is a front elevational view taken from the front of FIG. 2, the rear elevational view is a mirror image;

FIG. 11 is a right end view taken from the right end of FIG. 8; and,

FIG. 12 is a bottom plan view taken from the bottom of FIG. 8.

The handle is partially shown in FIGS. 2, 4, 6, 8, 10 and 12 for convenience of illustration.
